[57] ABSTRACT

A device is described herein for use in deactivating automobile door-operable switches. The device basically comprises a non-stretchable elongated strap having the ends thereof fixed to magnetic elements. A central portion of the strap is exposed of sufficient length to enable the magnetic elements to be secured to a door post on either side of a door-operable switch. When in position, the central portion of the strap engages and holds the switch button depressed to enable an individual to leave the vehicle door open without activating the dome light or warning buzzer usually activated by the switch.

DEVICE FOR DEACTIVATING AUTOMOBILE DOOR OPERABLE ELECTRIC SWITCH

BACKGROUND OF THE INVENTION

The device of the present invention relates basically to the area of automotive accessories and more particularly to a device for enabling selective deactivation of the common door post switch that normally serves to activate the vehicle's dome light and, in the new model vehicles, a "door open" warning buzzer, when the vehicle door is in an open condition.

It is frequently desirable in automobile repair work to open a vehicle door and leave it open over an extended period of time. This practice allows easy access for the repairman to the vehicle interior. Most present automobiles however, provide a switch located in the door opening, that automatically operates a warning "door open" buzzer and turns on a dome or map light, once a door has been opened. The repairman therefore de-activates the electrical circuit connecting the buzzer and light. This is done basically for two reasons: the first being the fact that the warning buzzers are designed to produce a substantially undesirable and irritable sound when frequently operated or when operated continuously over a length of time; and secondly, because both the dome light and the buzzer produce a drain on the vehicle battery. The repairman usually de-activates the electrical circuit by removing the over-load fuse connected in the circuit. Often this fuse is also interconnected with other circuits that could be desired to be operable for repair purposes. Further, it is often a somewhat tedious task to first locate the fuse box, locate the proper fuse, and finally remove the fuse and store it until a later time when it may be replaced. Such fuses are normally rather small and are easily misplaced or broken.

Consequently it is desirable to obtain a device for de-activating the door operable switch that is easily attached to and removable from the switch.

A U.S. Pat. No. 2,786,911 granted to R. C. Morgan, discloses a switch cutout for automobile doors that is comprised of a bracket permanently mountable to a door post, and a slidable plate mounted to the bracket that is operable to slide between an operative position wherein the plate engages and depresses the switch button to deactivate the dome light circuit, and an inoperative position spaced away from the switch to allow it to be normally operated upon opening and closing the associated door. Although this device allows selective operation of the door activated switch, it also must be mounted as a substantially permanent fixture to the subject automobile.

A similar device to the R. C. Morgan invention is disclosed in the E. J. Fiorucci U.S. Pat. No. 2,656,427 which also discloses an automobile switch deactivator that is mounted as a permanent fixture adjacent to the door-operable switch. An additional patent granted to J. H. Schultz, U.S. Pat. No. 2,856,477 also discloses a device for controlling door-operable electric switches that includes a bracket mounted as a substantially permanent fixture to the door post of an automobile and further, includes a slidable button depressing plate which, like the R. C. Morgan device, may be shifted between an inoperative and operative position.

Of the above cited prior art, none disclose a device for deactivating a door-operable switch that is not nec-

essarily a permanent fixture mounted to an automobile. It would therefore be uneconomical and a substantially time-consuming task for an automobile repairman to install any of the above devices for his own purposes of deactivating the dome light and warning buzzer, and then either leave the device mounted to the vehicle or remove it once the repair work is finished.

It is therefore a primary purpose of the present invention to provide a device for deactivating door-operable switches that is readily and easily applied to and removed from substantially any vehicle door or door post.

It is an additional object of my invention to provide such a device that is very simple in construction and thereby inexpensive to manufacture and purchase.

It is a further object of my invention to provide such a device that is designed to enable intentional or accidental closing of a vehicle door on the device without doing damage to the door, the door post, the switch, or the device.

These and other objects and advantages will become apparent upon reading the following disclosure, which taken with the accompanying drawings describe a preferred and alternate form of my invention.

A BRIEF DESCRIPTION OF THE DRAWINGS

A preferred and alternate embodiment of the present invention is illustrated in the accompanying drawing, in which:

FIG. 1 is a cross-sectional view of a door post and door operable switch with the device of the present invention mounted thereon;

FIG. 2 is a plan view of the device;

FIG. 3 is a longitudinal section taken along 3-3 in FIG. 2;

FIG. 4 is a plan view of the device in an alternate form; and

FIG. 5 is a cross-sectional view taken along 5-5 in FIG. 4.

DETAILED DESCRIPTION OF A PREFERRED AND ALTERNATE EMBODIMENT

Referring now to the drawings in greater detail, the device of a preferred form of my invention is illustrated in FIGS. 1, 2 and 3. An alternate form of the device is illustrated in FIGS. 4 and 5. The device of both the alternate and preferred forms is intended for use on vehicles having door-operated switches such as that generally designated by the reference numeral 10 in FIG. 1. Such switches 10 are utilized to close an electrical circuit upon the opening of an associated vehicle door 13. The circuit supplies electrical energy to operate a dome light and/or a "door open" warning buzzer. The switch 10 is usually situated on a metal door post 12 adjacent the hinged side of the vehicle door 13 as shown in FIG. 1. The switch 10 includes a spring-biased operating button 11 which is normally urged to an outward position. The outward position of the button 11 is shown by dashed lines in FIG. 1. This outward position of button 11 denotes an activated condition of the switch 10 wherein the dome light and buzzer circuit is closed. To deactivate or open the buzzer and dome light circuit, the button 11 must be depressed to the deactivated position illustrated in FIG. 1 by solid lines. This may be accomplished by closing door 13 or by utilizing the present invention.

The device is basically comprised of an elongated strap 14 having outer ends 15 mounted to a magnet means 18. It is designed to enable a repairman to easily and quickly deactivate the switch 10 without necessitating tampering with the electrical circuitry of the vehicle.

As illustrated in FIG. 1, the button 11 is depressed by simply applying the device to the door post 12 over the switch 10 with a central strap portion 19 of the strap 14 engaging the button and with the magnet means 18 clamped to the post 12 on either side of the button 11. The magnetic force supplied by magnet means 18 serves to support the device on the doorpost and hold the strap against the button to overcome the tendency of the button 11 to move to the extended or operative position.

The flexible strap is intended to be constructed of metal or synthetic resin having flexible or bendable but non-stretchable properties that provide sufficient longitudinal rigidity to hold the button 11 in a depressed position upon placement of the magnet means 18 on the door post 12. The flexible nature of the strap 14 facilitates mounting of the device to door posts having differing contours or configuration in the area of switch 10.

In the preferred form, the magnet means is comprised of a pair of magnetic discs 16. The ends 15 of the strap 14 are secured to the magnetic discs 16 by rivets 24 and metal washers 26. The rivets 24 extend through appropriate apertures formed through the discs 16 to mount the strap 14 between the disc surfaces and the washers 26. Recesses 28 are provided in one side of the discs to enable flush mounting of the magnet means to the door post 12.

The strap 14 of both embodiments illustrated is of sufficient length between ends 15 so that the central portion 19 is exposed over a distance greater than the diameter of button 11, thereby enabling engagement of portion 19 with the button 11. It may be noted in FIG. 1 that the overall thickness of the device, or the distance illustrated in FIG. 1 between the surface engaging the post 12 and the ends of rivets 24, preferably is 0.375 inches, or a distance slightly less than the distance between the post 12 and the end of button 11 when in the inoperative position. By constructing the device as such, I am able to prevent damage to the vehicle or device by accidental or inadvertent closing of the door 13 with the device still in place on the door post 12.

Looking now at FIGS. 4 and 5, it may be seen that the alternate form of the present invention simply utilizes a horseshoe shaped magnet 32 in place of the magnetic discs 16. In this embodiment, the strap 14 is mounted by the rivets 24 and washers 26 to opposite ends 34 of

the horseshoe magnet 32. The distance between ends 34 of the horseshoe magnet is sufficient to enable the magnet to be placed with a side 35 against the door post 12 with the exposed central section 19 of strap 14 engaging and depressing the button 11. The overall thickness of the second form is similar to that described above for the preferred form.

In operation of both described embodiments, the door 13 is opened to expose the button 11. The device 10 is then placed over the button with the central strap portion engaging the button and with the magnet means attached magnetically to the door post. The magnetic force of the magnet means 18 and the longitudinal rigidity of the strap 14 is sufficient to hold the button in the depressed position until the device is removed therefrom.

It may have become obvious from the above description and attached drawings, that various changes and modifications may be made therein without departing 20 from the intended scope of the present invention. It is therefore intended that only the following claims be taken as definitions of the invention.

What I claim is:

1. A device for deactivating an automobile door-operable electric switch comprising:

an elongated flexible, non-stretchable strap; magnet means fastened to the ends of the strap for releasably mounting the device to a door post of an automobile;

said strap including an exposed central portion adapted to contact and depress an operating button of door-operated electric switch to a deactivated position;

wherein the strap and magnet means have an overall thickness dimension less than a distance between the door post and the button with the button in the deactivated position.

2. The device set out in claim 1 wherein the magnet means comprises a pair of magnets mounted to the ends of the strap.

3. The device set out in claim 1 wherein the magnet means comprises a horseshoe-shaped magnet with the strap being mounted between ends of the horseshoe magnet.

4. A device for deactivating an automobile door-operable switch comprising:

an elongated non-stretchable strap; magnet means for releasably holding the strap to an automobile door post adjacent the switch; rivets mounting the magnet means to the ends of the strap; and

an exposed central portion of the strap adapted to engage and operate the switch.
